(57) **CLAIM**

The ornamental design for an umbrella cap, as shown described.

DESCRIPTION

FIG. 1 shows a perspective view of a design for an umbrella cap.

FIG. 2 shows a first side view of the design.

FIG. 3 shows a second side view of the design, rotated 1/16 of a turn relative to the first side view in FIG. 2.

FIG. 4 shows a top view of the design; and,

FIG. 5 shows a perspective view of the design in use in an umbrella.

The broken-line features in the figures are for illustrative purposes only and form no part of the claimed design. The umbrella in FIG. 5 is unclaimed environmental subject matter.
